UNITED STATES PATENT OFFICE

WALTER NICOLET, OF LEIPZIG, GERMANY

METHOD AND MEANS FOR MAKING A TEXTILE PRODUCT

Application filed May 26, 1927, Serial No. 194,382, and in Germany June 3, 1926.

My invention refers to the art of weaving and it particularly concerns means whereby the speed of weaving and in accordance therewith the quantity of woven fabric produced per unit of time are materially increased. These means comprise improvements in looms of the kind disclosed in my copending application for patent of the United States, Serial No. 73,718, filed December 7, 1925, in which two groups of warp threads extending at an angle to each other were acted upon to form two sheds, one in front of the other, a weft or wefts being entered into these sheds either simultaneously or one after the other. The warp threads belonging to the two groups were guided in the teeth of combs, one such comb being provided for each group and these guide combs were reciprocated vertically to form sheds, the casting of the weft onto the fabric being effected by means of reeds reciprocating substantially in horizontal direction. The weft material was entered into the sheds by means of shuttles of different kinds.

The present improvement is more particularly concerned with the passing of the wefts through the front shed. It further concerns means, whereby the weft is held in position during and after the weaving operation and it comprises also the novel kind of fabric obtained in the operation of my invention.

The entering of the weft in the front shed is effected according to this invention only from one side of the loom, the weft thread being guided by a needle provided with an eye through which extends the thread wound on the stationary weft bobbin. When entering the needle and weft thread in the front shed, a loop is formed, the two parts of which are cast onto the fabric separately. The loop formed in entering the thread is held in position by means of a tooth gripping the same shortly before the needle starts on its return stroke, and this tooth is

withdrawn only shortly before the second part of the loop is cast onto it.

In the drawings affixed to this specification and forming part thereof my invention is illustrated diagrammatically by way of example.

In the drawings—

Fig. 1 is a diagrammatic plan view showing the two groups of warp threads, the needle and the way in which this needle enters the weft threads in the front shed.

Fig. 2 is a side elevation corresponding to Fig. 1.

Fig. 3 is a view similar to Fig. 1 and showing the needle on its return stroke.

Fig. 4 is a side elevation corresponding to Fig. 3.

Figs. 5-8 show the means for holding the weft in position during and after the weaving, Figs. 5 and 7 being side elevations, while Figs. 6 and 8 are plan views.

Referring to the drawings, 1 and 2 are the two warp beams, 3 and 4 are the two groups of warp threads and 5 and 7 are the vertically reciprocable combs guiding the warp threads and moving in opposite direction. If the eyes of the combs are in line with each other, the threads of both groups extend from the combs towards the edge 8 of the fabric in one plane, while forming an angle towards the two warp beams. If the two combs are then moved in opposite directions away from each other, the angle will open towards the fabric. On the other hand if the two combs are moved past each other, there is formed besides the open shed directed towards the warp beams another shed which is closed and is directed towards the fabric. As explained above, weft threads are entered into both these sheds, these threads being cast onto the fabric one after the other, the weft extending through the rear shed during the time, when the angle formed by the two groups of warp

threads is open from the edge of the fabric on.

As far as the present invention is concerned, the entering of the weft in the rear shed is of no particular importance and it is assumed for the purpose of this invention that a simple weft thread is entered into the rear shed by means of a needle 50 moving at right angles to and between the rear ends 10 of the warp threads. According to the present invention the weft to be entered in the front shed is always introduced from one side of the loom in the form of a loop. The insertion of this loop is effected by 15 means of a needle 21 with an eye 22 through which extends the thread of the weft bobbin. To the needle 21 is secured near the eye 22 and on the side facing the fabric 8 a strap 23 which is also provided with an 20 eye 24. After the two groups of warp threads have been moved into the position shown in Fig. 2, where the closed front shed has been formed, the needle 21 carrying the weft thread enters into this shed. The strap 25 provides that the two parts of the weft thread forming the loop are spaced a considerable distance so that a reed made up of a series of dents 25 extending through the warp from below can enter the loop 30 after the needle has reached the end of its course. In this position the needle 21 remains stationary until the reed 25 rocking about a shaft 26 has cast onto the edge of the fabric that part of the loop which faces 35 this edge. While this is effected a tooth 29 forming part of an arm 28 intermittently rocking about a bolt 27 is moved in position behind the part of the weft which has been cast on, and retains the loop when the reed 40 25 has been rocked backwards and the needle 21 is withdrawn from the shed. When the needle 21 has reached its initial position, the reed 25, being inserted anew in the warp, will cast the rear part of the loop onto the 45 edge of the fabric after the fabric has first been wound up by positive action. The sheds are now changed and the tooth 29 is withdrawn from the loop, which is now tied up in the fabric. After the fabric has been 50 wound up a further step, the weft thread 11 introduced into the rear shed and pushed forward by suitable means is cast onto the edge of the fabric, whereupon the two groups of warp threads are crossed again 55 and after a further winding up of the fabric the cycle of operations is started afresh. By entering the weft threads in the front shed in the form of a loop and by separately casting on the two parts of the loop, the output obtained is increased further, the fabric obtained being absolutely uniform.

In case that the weft entered into a shed should not be stretched tightly or should be torn, it may happen that during the casting-on motion of the reed 25 only part of the

thread is caught by it, while the other part is left behind. In such a case the reed in rocking backwards would meet this latter part of the weft. If the bars of the reed were formed as usual, they would force this part of the weft across the warp threads and these latter would be stretched to such an extent that they would be torn as a rule. However, any tearing of warp threads amounts to a stopping of the loom and to a diminution of output. In order to prevent this, the single members constituting the reed 25 have outwardly curved backs, the convex edge facing the combs 5, 7. If a reed thus shaped meets parts of the weft which happen to be left behind, it will owing to its convex rear edge merely force the weft thread backwards without forcing it across the warp threads and these latter threads are therefore protected against tear- 75 80 85

As shown in Figs. 1 and 3, the finished fabric has a closed edge only on that side, on which the front weft is entered, while on the other side the warp threads are not tied up and can therefore easily be withdrawn from the fabric. However, if the outermost warp threads are loosened, the weft threads will also lose their support on this side. In order to obviate this drawback, a separate edge warp thread 30 is provided, which comes from a bobbin 31 and is guided by a lever 32 provided with an eye, but has no connection with the combs 5, 6 and is not moved together with the warp threads 3, 4. To lever 32 is imparted an independent reciprocatory movement of its own, whenever the thread guide 20 for the rear weft returns from that side, where the edge warp thread 30 is arranged, towards the side, where the front weft thread is entered. Owing to this arrangement the edge warp thread is embraced by the rear weft thread and is thus fixed in the fabric. On the other hand the edge warp thread ties up the loop formed in the rear weft thread by a reciprocatory movement of the thread guide 20 imparted to it from that side of the fabric, on which the front weft is entered, while the rear weft thread is tied up on the other side as usual. It is true that the loop entered in the front shed is not tied up at that edge of the fabric where the edge warp thread is arranged, however, this is of no importance as far as the strength of the fabric is concerned. 100 105 110 115 120

I wish it to be understood that I do not desire to be limited to the exact details of construction shown and described for obvious modifications will occur to a person skilled in the art.

I claim:—

1. The method of producing a fabric by weaving comprising moving the warp threads so as to form a shed and inserting in 125 130

said shed a weft in the form of a loop and casting on first that part of the loop which faces the edge of the fabric, and only thereafter the other part.

5 2. The method of producing a fabric by weaving comprising moving the warp threads so as to form in each operation two sheds, one to the rear of the other and passing a weft through each shed, the weft entered in the front shed having the form of a loop and the two parts of this loop being cast on separately.

10 3. The method of producing a fabric by weaving comprising moving the warp threads so as to form a shed and passing a weft through said shed, the weft being entered always from one and the same side and having the form of a loop, the two parts of this loop being cast on separately.

15 4. The method of producing a fabric by weaving comprising moving the warp threads so as to form a shed, passing a weft through said shed, having the form of a loop and the two parts of this loop being cast on one after the other, gripping this loop and releasing same only shortly before its rear part is cast on.

20 5. The method of producing a fabric by weaving comprising moving the warp threads so as to form in each operation two sheds, one to the rear of the other, passing a weft through each shed, the weft being entered in the front shed always from one and the same side and having the form of a loop casting on the two parts of this loop and moving the outermost warp thread on the opposite side independently of the other warp threads in such manner that it is tied up by the weft entered in the rear shed.

25 6. A loom comprising means for moving the warp threads so as to form two sheds, one to the rear of the other, in alternate shedding operations, means for entering a weft thread having the form of a loop in the front shed and a single weft thread in the rear shed and means for casting the two parts of the looped weft on separately.

30 7. A loom comprising means for moving the warp threads so as to form two sheds, one to the rear of the other, in alternate shedding operations, a needle with an eye for entering a weft thread in the front shed in form of a loop, separate means for entering a weft thread in the rear shed and means for casting the two parts of the looped weft on separately.

35 8. A loom comprising means for moving the warp threads so as to form two sheds, one to the rear of the other, in alternate shedding operations, means for entering a weft thread having the form of a loop in the front shed and a single weft thread in the rear shed means for gripping said loop shortly before said thread entering means

starts on its rear stroke and means for casting on said weft threads.

9. A loom comprising means for moving the warp threads so as to form two sheds, one to the rear of the other, in alternate 70 shedding operations, means for entering a weft thread having the form of a loop in the front shed and a single weft thread in the rear shed, means for gripping said loop shortly before said thread entering means 75 starts on its rear stroke, means for casting the two parts of the looped weft on separately, and means for withdrawing said gripping means shortly before the rear part is cast on.

10. A loom comprising means for moving the warp threads so as to form two sheds, one to the rear of the other, in alternate shedding operations, means for entering a weft thread having the form of a loop in 80 the front shed always from one and the same side and a single weft thread in the rear shed and means for casting the two parts of the looped weft on separately.

11. A loom comprising means for moving 85 the warp threads so as to form two sheds, one to the rear of the other, in alternate shedding operations, means for entering a weft thread having the form of a loop in the front shed always from one and the same side, and a single weft thread in the rear shed means for casting on said weft threads and means for moving the outermost warp thread on the opposite side independently of the other warp threads in 90 such manner that it is tied up by the weft entered in the rear shed.

12. A loom comprising means for moving the warp threads so as to form two sheds, one to the rear of the other, in alternate 105 shedding operations, a needle with an eye for entering a weft thread in the front shed in form of a loop, weft-guiding means on said needle, near the eye forming part thereof, for keeping the two parts of said loop in spaced relation and separate means for entering a weft thread in the rear shed and means for casting on said weft threads.

13. A loom comprising means for moving the warp threads so as to form two sheds, one to the rear of the other, in alternate 110 shedding operations, a needle with an eye for entering a weft thread in the front shed in form of a loop, strap-shaped weft-guiding means on said needle, near the eye forming part thereof, for keeping the two parts of said loop in spaced relation and separate means for entering a weft thread in the rear shed and means for casting on 115 said weft threads.

14. A loom comprising means for moving the warp threads so as to form two sheds, one to the rear of the other, in alternate 120 shedding operations, means for entering a weft thread having the form of a loop in 130

the front shed and a single weft thread in the rear shed and a reed and dents thereon having outwardly curved backs for casting on the front part of said loop and means for casting on the rear part thereof and the single weft thread.

15. The method of producing a fabric by weaving comprising moving the warp threads so as to form a shed and inserting in said shed a weft in the form of a loop, the two parts of the weft thread forming the loop being spaced a considerable distance, and casting on first that part of the loop which faces the edge of the fabric, and
10 only thereafter the other part.

In testimony whereof I affix my signature.

WALTER NICOLET.
